CLAIM

I claim the ornamental design for a holder for an oral hygiene device, as shown and described.

DESCRIPTION

FIG. 1 is a front perspective view of an embodiment of a holder device;

FIG. 2 is a back perspective view thereof;

FIG. 3 is a front view thereof;

FIG. 4 is a back view thereof;

FIG. 5 is a first side view thereof;

FIG. 6 is a second side view thereof;

FIG. 7 is a top view thereof; and,

FIG. 8 is a bottom view thereof.

Broken lines are used to illustrate features and/or environmental structures and form no part of the claimed design. Broken dot-dash lines are used to indicate a border of the claimed design and form no part of the claimed design. The broken lines immediately adjacent the claimed surfaces represent boundaries of the claim, which extends to the boundaries, but does not include the boundaries; all other broken lines depict portions of the holder for an oral hygiene device that form no part of the claim. The break lines illustrate a variable length and form no part of the claimed design. The space between the break lines also forms no part of the claimed design. The holder for an oral hygiene device is shown with a symbolic break in its length. The appearance of any portion of the article between the break lines forms no part of the claimed design.
